[57] CLAIM

The ornamental design for a combined control unit and holder for dental equipment, as shown and described.

DESCRIPTION

FIG. 1 is a perspective view taken from the upper left side of a combined control unit and holder for dental equipment showing our new design;

FIG. 2 is a top plan view thereof;

FIG. 3 is a right side elevational view thereof;

FIG. 4 is a bottom plan view thereof; and

FIG. 5 is a rear elevational view thereof.

The broken line showing of environmental structure is for illustrative purposes only and forms no part of the claimed design.
